UNITED STATES PATENT OFFICE.

JULIUS LITTMAN, OF NEW YORK, N. Y.

FOOT-FORM ARCH-SUPPORT.

1,208,176.

Specification of Letters Patent. Patented Dec. 12, 1916.

Application filed April 10, 1916. Serial No. 90,055.

To all whom it may concern:

Be it known that I, JULIUS LITTMAN, a subject of the Emperor of Austria-Hungary, residing at 1518 First avenue, New York, county of New York, and State of New York, have invented certain new and useful Improvements in Foot-Form Arch-Supports, fully described and represented in the following specification and the accompanying drawings, forming a part of the same.

My invention relates to an instep arch-support adapted to be manufactured and sold independent of the shoe, and having a bottom-plate proportioned to fit within the same over the shank and heel of the sole.

The bottom-plate is preferably made of metal so that integral flanges can be extended up therefrom to fit the opposite sidewalls of the shoe. Besides these features of the bottom-plate, the invention embraces a particular construction for the arch-plate and the means for supporting it yieldingly upon the bottom-plate.

The invention will be understood by reference to the annexed drawing, which shows the fixtures secured within a shoe, and also certain of the parts in detail.

In the drawing, Figure 1 is a longitudinal section of the rear portion of a shoe having the arch-support applied thereto; Fig. 2 is a plan of the sole of the shoe (with the fixtures applied thereto) in section just above the level of the fixtures; Fig. 3 is a cross section on line 3—3 in Fig. 2, and Fig. 4 shows the under side of the arch-plate with its supporting springs. Fig. 5 is a plan of the sole of the shoe and the cover-piece of the arch-plate.

The sole of the shoe at the shank is designated *a*, and the heel *b*. The bottom-plate *c* of the fixture is proportioned to fit over the shank and over the heel, and is shaped to fit closely against the counter *d*, and its rear end secured by nails or screws *f* inserted through the cover-piece *n* and the heel. Flanges *c'* and *d'* extend upwardly from the plate *c* at opposite sides to fit within the sides of the shoe, and a low flange *d''* extends within the counter *d*.

The arch-plate *g* is shaped to suit the foot of the wearer, and fits against the flange *d'* at one side of the bottom-plate. At its opposite edge, it is formed with several slots *h* and smooth headed rivets have their shanks

inserted through the slots and secured in the bottom-plate *c*.

Spiral springs *i* are inserted between the bottom-plate and the arch-plate, being located at different points to sustain the pressure over such points. These springs operate in an entirely different manner from leaf-springs, which yield only at the middle of their length and thus furnish an elastic support at one point only; whereas the spiral springs may be inserted in any required number, and each one be enabled to yield in proportion to the pressure upon it.

The springs shown are of the form made of a V-shaped piece of sheet-metal wound to produce spiral coils at each side of its middle portion, such coils pressing one within the other when the spring is loaded, and such springs presenting a maximum endurance and supporting power in a given space.

A rubber block *s* is inserted under the arch-plate *g* near the slots *h* where there is not space enough for spiral springs.

The slotted connection of the arch-plate to the bottom-plate permits the arch-plate to expand laterally when it is pressed by the foot, while it holds the arch-plate from any longitudinal displacement.

Over all of the fixtures so far described, is secured a cover-plate *n* consisting of leather fitting the bottom of the shoe and secured within the heel by tacks *f*. Such cover-piece extends wholly over the arch-plate, and its free end is held movably to the sole beyond the arch-plate by pin-and-slot connections *h*, shown in Figs. 1 and 2, which form a slip-joint with the sole. Such cover-piece distributes the pressure of the arch-plate upon the foot and protects all the other parts from wear. The slotted connection *p* permits the cover-piece to slip on the sole as it is pressed down by the foot.

The bottom-plate with its integral flanges *c'* and *d'*, is made of thin metal so as to occupy no material space within the shoe, and the flanges *c'*, *d'* and *d''* retain it in position independently of all other means. The flanges may be lined with cloth, felt, or a thin layer of asbestos, if desired, and such a layer is indicated at *l* in Fig. 3.

Owing to the thinness of the metallic bottom-plate *c*, I prefer to reinforce it under the springs *i* by a thin steel plate *m* which may be secured to the bottom-plate by rivets *m'*.

The springs *i* and *s* do not lose their elasticity as many leaf-springs do, and my arch-support is therefore very durable. The cover-piece *n* supports the foot more effectively than a mere arch-plate; and the device is thus rendered comfortable to the wearer.

Having thus set forth the nature of the invention what is claimed herein is:

- 10 1. An arch-support for insertion within a shoe, consisting of a bottom-plate adapted to extend over the shank and heel of the shoe, and an arch-plate connected to the bottom-plate over the shank of the shoe by transversely slotted connections, and having a plurality of spirally wound springs fitted between the bottom-plate and the arch-plate.
- 15 2. An arch-support for insertion within a shoe, consisting of a bottom-plate adapted to extend within the heel and having flanges extended upwardly therefrom to fit the side-walls of the shoe, and an arch-plate connected to the bottom-plate over the shank of the shoe by transversely slotted connections, and having a plurality of spirally wound springs fitted between the bottom-plate and the arch-plate.
- 20 25

wound springs fitted between the bottom-plate and the arch-plate.

3. An arch-support for insertion within a shoe, consisting of a metallic bottom-plate 30 adapted to extend within the heel and having integral flanges extended upwardly therefrom, and an arch-plate connected to the bottom-plate over the shank of the shoe by transversely slotted connections, and having a plurality of spirally wound springs fitted between the bottom-plate and the arch-plate. 35

4. An arch-support for insertion within a shoe, consisting of a bottom-plate, an arch-plate connected to the bottom-plate over the shank of the shoe by transversely slotted connections, and having a plurality of spirally wound springs fitted between the bottom-plate and the arch-plate, and a cover-plate applied over the whole and secured within the heel and provided at its free end with a slip-connection to the sole. 40 45

In testimony whereof I have hereunto set my hand.

JULIUS LITTMAN.
